(57) **CLAIM**

The ornamental design for a microscope, as shown and described.

DESCRIPTION

FIG. 1 is a front, top and left side perspective view of a microscope showing our new design;

FIG. 2 is a rear, top and right side perspective view thereof;

FIG. 3 is a front elevational view thereof;

FIG. 4 is a rear elevational view thereof;

FIG. 5 is a right side view thereof;

FIG. 6 is a left side view thereof;

FIG. 7 is a top plan view thereof;

FIG. 8 is a bottom plan view thereof;

FIG. 9 is a front, top and left side perspective view thereof, showing a state with an objective lens attached thereto; and, FIG. 10 is a front, top and left side perspective view thereof, showing a state of use.

The portions of the drawings shown in broken lines are for illustrative purposes only and form no part of the claimed design.
